GASKET

George A. Barker, Rochester, N. Y.

Application October 20, 1932. Serial No. 633,769

9 Claims. (Cl. 288—1)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates to gaskets and more particularly to the type of gaskets made up of a plurality of layers one of which is a reinforcement and the others of which preferably comprise compressible material, the invention having 10 for its object to provide a construction which may be cheaply manufactured and which is more efficient in use than those heretofore employed.

With these and other objects in view the invention resides in the novel details of construction 15 and combinations of parts as will be disclosed more fully hereinafter and particularly pointed out in the claims.

Referring to the accompanying drawing forming a part of this specification in which like 20 numerals designate like parts in all the views,

Fig. 1 is a perspective view of a portion of the reinforcement of cellular nature constituting one of the layers of the complete gasket;

Fig. 2 is a top plan view of one type of reinforcement contemplated by this invention;

Fig. 3 is a side elevation of the reinforcement shown in Fig. 2 with compressible material placed on either side thereof;

Fig. 4 is a side elevation of the construction shown in Fig. 3 after pressure has been applied to the outer surfaces thereof;

Fig. 5 is a top plan view of another form of cellular reinforcement made in accordance with this invention;

35 Fig. 6 is a sectional view taken as on the line 6—6 of Fig. 5 and looking in the direction of the arrows, this figure showing the compressible material associated with said reinforcement;

Fig. 7 is a sectional detail illustrating a modification of the cellular structure of the reinforcement;

Fig. 8 is a sectional detail illustrating a modification of the enveloping layer construction; and

Fig. 9 is a side elevation showing a gasket, made 45 in accordance with this invention, applied between the flanges of adjacent sections of piping.

In order that this invention may be more properly understood it is said that in heretofore known gasket constructions there has not been 50 a uniform thickness throughout said gasket, particularly in the case of gaskets made by laminating metallic and fibrous material. This result was caused by protuberances formed by portions of the metallic element, or separate metallic elements, employed to hold the laminated gasket to-

gether. Therefore, leaks commonly occurred from such heretofore known constructions, caused by an incomplete seal due to said protuberances, to the end that cements of various kinds including varnish had to be used as a preventive measure 60 but, where such gaskets were used between members of a mechanical assemblage in which high heat was developed, these cements have been affected by the heat to the end that they usually boiled out, and thus any advantage of said cements was lost. This invention, on the other hand, is directed to the provision of a gasket made up of plural layers one of which is of metallic and cellular construction, the remaining layers being formed of compressible and/or penetrable 70 material.

Referring to the drawing, 1 generally indicates the layer of metallic reinforcement which is of cellular construction, the cells in Fig. 1 being 75 parallelly disposed with reference to each other and openly extending entirely through said layer. These cells may be of various cross sectional area and shape that is they may be polygonal as indicated in Fig. 1, hexagonal as shown in Fig. 2, square as shown in Fig. 5, or of any 80 other shape including circular and in this latter case the layer could be made by soldering, welding, or otherwise securing a plurality of circular tubes in mass formation.

A layer 2 of compressible material such as 85 asbestos wool, rubber, cork, treated paper, or any other suitable substance, and which preferably is treated with water-proofing substances such as resines, oleates, bitumens or asphalts, is applied to one of the sides of the reinforcement so as to cover one end of the cells of the latter. A similar layer 3 is applied to the opposite side of the reinforcement to cover the other end of said cells. The layers 2 and 3 may 90 be cemented or not to the reinforcement, this invention also contemplating other means of securing than cement, such as stitching, and the attachment of the various layers may be accomplished by partially compressing the layers 2 and 3 into the open ended cells of the 95 reinforcement, and/or bending or crimping the cellular wall about portions of the compressible material extending into the open ends of the cells. In Fig. 3 is particularly shown the result of this partial compression resulting in the 105 portions 4 of the compressible material entering appreciably the open end of some of the cells of the reinforcement.

Further compression of the laminated gasket shown in Fig. 3 produces a construction illus- 110

trated in Fig. 4 wherein the metal reinforcement is squashed, the upper and lower portions of said gasket having moved in opposite directions resulting in an oblique disposition of the central portions of the cells of the reinforcement and a curving or crimping of the extreme ends of the cells about the portions 4 of the compressible material. This results in a positive lock between the reinforcement and the compressible material while maintaining the cellular nature of the reinforcement. It is to be understood, of course, that this additional compression of the laminated gasket is only sufficient to bring about said locking relation, and is not so great as to cause a complete mashing with consequent destruction of the cells, wherefore said gasket may be still further compressed when drawing up the adjacent ends of the mechanical assemblage between which the gasket is used as a seal.

From the foregoing description it will therefore be understood that this invention is directed to the formation of a gasket each of the layers of which have parallel plane surfaces so that, when the gasket is finally laminated, the exposed sealing surfaces 5 and 6 will lie substantially in parallel planes, which is the normal desire in all gaskets. When such a gasket is inserted, for instance, between the flange 7 of a pipe 8 and the flange 9 of an adjacent substantially aligning and similar pipe 10 then a tightening of the bolts 11 and 12, passing through said flanges, will compress said gasket and cause a seal of the joint between the surfaces 5 and 6 thereof and the surfaces of said flanges. If the bolts 11 and 12 are evenly tightened then the gasket will have substantially equal compression throughout.

On the other hand, and as distinctly shown in Fig. 9, this laminated gasket is of such construction that unequal tightening of said bolts will still cause a complete seal, due to the fact that the extremely thin walls of the cells of the reinforcement will yield under the variable pressures on said bolts. The inherent spring in the metal of these walls will prevent a permanent set in this portion of the laminated gasket, wherefore said bolts do not have to be tightened with the extreme care that might be expected, although they will be tightened to such a degree as to cause the desired seal. Also the yieldable nature of the compressible material will create an internal stress or pressure in the body of the laminated gasket, to the end that the external surfaces 5 and 6 of said gasket will lie in sealing contact with the surfaces of the flanges 7 and 9. This is markedly contrasted to the seals made by heretofore known types of gaskets whose inner layer is soft fibrous material and whose outer layers are metallic, usually requiring a fine machining of the surfaces of the flanges 7 and 9 to create the sealing contact with the gasket, and also contrasted to the improper seal caused by the heretofore mentioned protuberances created by the locking means for securing the metallic members to the fibrous material of said heretofore known gaskets.

In the construction shown in Figs. 5 and 6, the cells are of square cross sectional area, and arranged in parallel rows as shown. However, these cells are obliquely disposed in the block forming the reinforcing layer and, further, the inclination of the alternate rows is different from the inclination of the intermediate rows. That is to

say, the cells of the row 15 are inclined as shown in Fig. 6 from upper right to lower left whereas the cells of the next adjacent row 16 are inclined from upper left to lower right. This results in a substantial strengthening of the reinforcing layer so that, for example, when a laminated gasket made according to this construction is placed between the flanges 7 and 9 and the bolts 11 and 12 tightened, the open ended cells of the reinforcement will bite deeper into the layers 2 and 3 of compressible material in accordance with the increase of pressure applied on the securing bolts.

In other words, this oppositely directed cellular construction of the reinforcement is maintained to a greater degree, upon the application of pressure on opposite sides of the laminated gasket, than is possible with the construction shown for example, in Fig. 3, and therefore the former is not deformed to as great an extent as in the case where all of the cells of the reinforcement are parallelly disposed to each other. A construction according to the showing in Figs. 5 and 6 would be more desirable where extreme pressures were exerted at the joint being sealed, such as in the case with extremely high pressures in the piping 8-10 or where great rigidity was desired with respect to the mechanical assemblage. Otherwise the same principles are involved in the constructions of this reinforcement as in the other types illustrated.

An important feature of this invention is that, by any of these constructions, the major portion of the gasket is composed of cells of metallic material which is infinitely stronger than fibrous or other compressible material. In other words, the major portion of heretofore known gasket constructions has been material of compressible nature, and usually any metallic element in such a gasket has been confined to an envelop disposed about the compressible material; that is, there has been provided an inner layer of relatively soft compressible material of appreciable thickness disposed between upper and lower layers of extremely thin sheet metal, the metal coming in contact with the surfaces of the mechanical assemblage such as the flanges 7 and 9. It therefore resulted that, when these extremely thin sheets of metal were ruptured, punctured or otherwise broken, the pressure and/or the substance within the mechanical assemblage could readily escape through the interstices of the compressible material.

As contradistinguished from this undesirable result it will be seen that this invention provides a metallic cellular construction constituting the major portion of the laminated gasket, the reinforcement being disposed centrally of said gasket. Upon applying pressure, as when forming the seal, the edges of the cells formed by this thin sheet metal bite deeper into the substance of the compressible outer layers of the gasket, and could substantially pass therethrough in certain instances. Therefore, any extremely high pressure within the piping 8-10 might rupture the walls of some of the cells of this reinforcement, but it is extremely improbable that it would cause a rupture which would extend clear through said reinforcement, whereby the pressure and/or substance in trying to escape from said piping through a ruptured cell would pass into and be confined in the next adjacent cell. Therefore it is an object of this invention to provide the cells with relatively small cross sectional areas and preferably it is contemplated to

- have such areas approximately equal to one-eighth of a square inch, although this dimension will be varied appropriately according to the conditions and usage for such a gasket. The thickness of the sheet metal forming the walls of these cells also may be varied in proportion to the pressure or usage for such a gasket, although with a cell area of one-eighth of a square inch, the thickness of the cell wall would be approximately one-sixty-fourth of an inch.
- In the modification illustrated in Fig. 7 the cellular principle is retained but, instead of the cells being continuous from one side to the other of the reinforcing layer, they are separated by a division wall 20. The side walls of the cells may be perpendicular to this division wall or they may be inclined with respect thereto, and also the cells such as 21 on one side of the division wall may be registrably superposed with respect to the cells such as 22 on the other side thereof or the cells 21 and 22 may have staggered relation.
- In Fig. 8 is shown a modification of the enveloping or covering layers wherein 1 is a core or central layer of cellular construction such as illustrated in Fig. 2, and 23 and 24 are respectively the upper and lower layers replacing the hereinbefore described layers of compressible material. In this modification the covering layers 23 and 24 are sheets of material having a surface which may be penetrated by the end edges of the cells of the core, the material contemplated including casting-metal, lead, soft copper or brass, type-metal and others, it being understood that the material used may or may not be softer than the metal of the cellular core. The inner surface of each of these layers 23 and 24 may be previously scored, or not as preferred, to establish seats for the edges of the cell walls.
- It is obvious that those skilled in the art may vary the details of construction and arrangements of parts within the scope of this invention without departing from the spirit of the invention, and therefore it is not desired to be limited to the foregoing description except as may be required by the claims.
- What is claimed is:
1. A gasket comprising a layer of cellular material, the cells arranged in rows, the cells of one row extending in a direction oblique with respect to the cells in the next adjacent row; and a layer of material capable of being penetrated by the end edges of the cells of said first named layer.
  2. A gasket comprising a layer of cellular reinforcing material; and a layer of gasket material, the cells of the reinforcing layer arranged in rows with the central axes of said cells oblique to the surface of the layers and inclined in opposite directions in alternate rows, said layers of reinforcing and gasket material being united by compression which partially forces the gasket material within the cells of the reinforcing material.
3. A laminated gasket including a layer of reinforcing material composed of honey-combed cells having deformable partitions and a layer of compressible gasket material, the gasket material partially projecting within said honey-combed cells and retained therein by the deformation of the cells.
4. A laminated gasket including a layer of reinforcing material constructed of honey-combed cells having deformable side walls, exterior adjacent layers of compressible gasket material with projecting protuberances extending within the cell passages and anchored therein by intercellular projections produced by the deformation of the side walls.
5. A laminated gasket including a layer of reinforcing material constructed of honey-combed cells having deformable side walls, exterior adjacent layers of compressible gasket material with projecting protuberances extending within the cell passages and anchored therein by interior projections of the side walls when deformed by external pressure.
6. A laminated gasket including a layer of reinforcing material composed of honey-combed cells having side walls adapted to be deformed under pressure, and an adjacent layer of compressible gasket material having protuberances projecting within the cells and anchored therein by restriction of the internal area of the deformed cells.
7. A laminated gasket including a central layer of reinforcing material composed of honey-combed cells having side walls adapted to be deformed under pressure, and exterior adjacent layers of compressible gasket material having protuberances projecting within the cells and anchored therein by restriction of the internal area of the deformed cells.
8. A gasket having a core layer of relatively rigid material with recesses extending inwardly from opposite sides of said layer and separated from each other by a common division wall, and layers of gasket material on opposite sides of said core layer adapted to be pressed into said recesses to compensate for variations in the contour of the surfaces between which the gasket is located.
9. A gasket having a core layer of relatively rigid material with recesses extending inwardly from opposite sides of said layer and separated from each other by a common division wall, said wall being substantially parallel to the outer surfaces of said core layer, and layers of gasket material on opposite sides of the said core layer adapted to be pressed into said recesses to compensate for variations in the contour of the surfaces between which the gasket is located.

GEORGE A. BARKER.
